Attorney.

UNITED STATES PATENT OFFICE

1,991,531

FUEL SEPARATOR AND VAPORIZER

Ernest M. White, Los Angeles, Calif.

Application October 26, 1928, Serial No. 315,317

4 Claims. (Cl. 48—180)

This invention relates to fuel separators and vaporizers, commonly called homogenizers.

An object of the invention is the provision of a device which effectively prevents the introduction of raw gasoline or other fluid into an engine manifold. Accomplishing this object, the device is so arranged that the trapped or raw gasoline or other fluid is forced into contact with the incoming stream of combustible fluid so that the same is homogenized.

At low engine speeds, the so-called suction or vacuum strokes are greatest, but the air velocity is not as high as when the engine is operating at high speed. This results in improper mixing between gasoline vapor and air. The present device incorporates means adapted to maintain a substantially uniform air velocity regardless of engine speed.

Other objects of the invention will appear as the specification proceeds, and with such objects in view includes a structure which is simple of construction, fool-proof in operation, and generally superior.

The invention consists in the novel and useful provision, formation, construction, association, and relative arrangement of parts, members and features, all as shown in a certain embodiment in the accompanying drawing, described generally, and more particularly pointed out in the claims.

30 In the drawing:

Figure 1 is a side elevation of an internal combustion engine incorporating the invention.

Figure 2 is a longitudinal sectional view of the invention.

35 Figure 3 is a fragmentary longitudinal sectional view of a modified form of the invention, and

Figure 4 is a fragmentary longitudinal sectional view of a modification of certain portions of the invention.

40 Referring with particularity to the drawing, I have shown an internal combustion engine A with the improved invention of the form shown in Figure 2 and designated as B associated with the intake manifold of the engine. The device B is adapted to work above and be associated with a carburetor a. In the present instance, the intake manifold b forms a part of the device B, although it is evident that the device B might be detachably secured to the manifold. A casing c is provided with inner and outer walls 1 and 2, respectively, adapted to form therebetween an annular space 3 and this casing is either detachably or integrally associated with the manifold b. In the present instance, the casing forms a part of the said manifold. The outer wall of said

casing is formed with annular flanges 4 and 5 which permit communication with the space 3. The base member 6 is integrally formed and interconnects the outer and inner walls 1 and 2. The manifold b forms a portion of the upper wall between said outer and inner walls, as shown at 7. The inner wall 1 is formed to have two portions of different diameters, as shown at 8 and 9, connected by a ledge portion 10. The manifold wall is formed with a circular opening 11 in alignment with the opening bounded by the walls 8 and 9. In the drawing, the diameter of the opening 11 is almost equal to the inner diameter of the portion 9, the manifold slightly overlapping or providing a flange portion, as shown at 12.

5 In the form of the invention shown in Figure 2, I have provided means d adapted to be confined by the wall 1. This means includes a tubular member which is flared at 13, and provided with a base or annular flange 14. In addition, the tubular member is circumferentially provided with one or more transverse slots 15. The base or annular flanged portion 14 is adapted to be interposed as between the base 6 and a flange 16' secured to the end of the carburetor casing or body 16. The usual gaskets 17 are provided to assure a leak-proof fit. Bolts or the like 18 pass through the flanges 14 and 16' and are screw-threaded to the base 6 to hold the several parts in assemblage. The means d is preferably concentric with respect to the curved wall 1 and likewise with respect to the part 16 of the carburetor a.

20 Means e is provided for regulating the velocity of fluid passed from the carburetor and into the intake manifold as well as controlling the deflection of such fluid. In particular, the said means includes a deflector plate 19, the deflector surface of which is curved upwardly and downwardly with respect to a central apex or point 20. This plate is enlarged at 21 to receive a pin 22. The manifold is enlarged and formed with an opening at 23, and a cap 24 is secured to the manifold and over said opening 23. The pin 22 extends within said cap. Interposed between a flange portion 25 of the cap and the enlarged portion of the manifold surrounding the opening 23 is a member 26. This member is provided with a web or diagonal piece 27 which is enlarged or reinforced, as shown at 28, and likewise formed with a transverse bore 29 through which bore the pin 22 is passed. One end of said pin carries an adjustable nut 30 and a coil spring 31 is adapted to be interposed between said nut 30 and the top surface of the cross piece or webbing 27. Compression of said spring is regulated by adjusting

the nut 30. Interposed between the deflector plate 19 and a portion of the manifold wall and surrounding the pin 22 is a resilient member 32. In the present instance, this resilient member is of the ordinary sylphon-bellows type. This sylphon may be secured to the deflector and to the manifold in any approved manner, such as by providing annular grooves in both the manifold and the top surface of the deflector for receiving ends of said sylphon-bellows. The sylphon thus closes entrance within the cap 24. The cap is provided with a transverse bore 33 and with a screw 34 for regulating passage of air or other fluid through said bore. The enlargements 4 and 5 are screw-threaded to receive nipples or the like 35 and 36. The nipple 36 in turn carries a tubular member 37 adapted to house a butterfly type of valve 38 and this member 37 in turn connects with tubing 39 leading to the exhaust manifold 40 of the engine. A tube 41 is secured to the screw-threaded portion of the part 4.

The form of the invention illustrated in Figure 3 does not differ in essential details from the form just described save and except that the means *d* is not utilized. Furthermore, in place of enlarging the base 6 to receive the flange 16' of the part 16 of the carburetor, a separate flange 42 is provided spaced from a base portion 43, and to the flange 42 is secured the flange 16' of the part 16 of the carburetor. In other particulars, the construction is the same save and except for the possible difference in the shape of the annular space 3.

In Figure 4, the construction would remain the same as shown in Figure 2 with the exception of the deflector means *e* which in the present instance is designated as *f*. This deflector is of the semi-fixed type although it may be formed of a material which is readily expandable and contractible. The bore of the manifold is formed with a screw-threaded bore 44 and a plug member 45 forming a part of the means *f* is adapted to be screw-threaded within said bore. This plug member carries a tubular part 46 terminating in a deflector head 47 identical in formation with the plate 19. The means *d* is also utilized. The means *f* has its deflector head spaced a determined distance above the means *d*, as shown in Figure 4.

In all the constructions illustrated that portion of the manifold may be enlarged where it surrounds the means *e*, as shown in Figures 2 and 3 at 48.

The operation, uses and advantages of the invention just described are as follows: Assuming that the engine is in operation, passage of air admixed with gasoline is regulated with respect to the carburetor by the throttle valve 49 and this air and gasoline admixed are passed upwardly through the means *d* and impinges against the curved surface of the deflector plate 19. Exhaust gases from the manifold 40 are directed under valved regulation into the space 3 for the purpose of heating the wall 1. If the engine is idling, the deflector plate will assume the dotted line position of Figure 2 and the combined mixture of air and gasoline will strike the curved surface of this deflector plate and be deflected against the shoulder 10, thence upwardly within the manifold through the opening 11. If raw gasoline strikes the deflector plate, it will be trapped on this shoulder which forms a pocket and will flow down the inner surface of the wall 1. There will be a reduced pressure

within the manifold and as air and gasoline in the carburetor rushes through the means *d*, a circulation will occur which will have as its path the space included between the means *d* and the inner surface of the wall 1 through the slots 15, into the air stream passing through the means *d*. This will be a continuous so-called longitudinal circulation. Thus, any heavy globules of not properly mixed gasoline will gradually be properly admixed with air due to this circulatory motion and such globules will be continuously deflected downwardly by the deflector plate until there is a proper admixture as between the air and gasoline, or other fluid. The deflector at idling speeds of the engine will assume the dotted line position of Figure 2 but at higher speeds the deflector will be raised, as indicated by the solid lines in said figure. The degree of raising or lowering is in a measure controlled not only by the reduced pressure within the intake manifold resultant upon engine speed, but likewise upon adjustment of the compression of the spring 31 by adjusting the nut 30. At idling speeds the reduced pressure is greatest but the air velocity is low. In order to properly admix the air and gasoline and to assure that solid globules of gasoline should not be directed into the intake manifold, the deflector plate moves downwardly so that the space included between the face of the deflector plate and the mouth of the means *d* should be restricted to the end that an orifice effect takes place so that the fluid velocity is maintained at a substantial uniform rate regardless of engine speed. The sylphon-bellows 32 helps to damp out oscillatory vibration that might otherwise occur in the deflector plate if the spring 31 was the only medium relied upon for holding the said plate. The screw 34 will of course regulate the air pressure back of the deflector plate, hence controlling movement of the plate, to the end that the deflector plate will always operate efficiently.

In the case of the form of the invention shown in Figure 3, the invention would perform in a similar manner, although the means *d* is not utilized. The inner diameter of the opening 8 would be restricted as to size so that the deflector plate would fit thereover. The results accomplished would be similar to the form of the invention shown in Figure 2 and raw globules of gasoline would flow down to be picked up again by the upwardly moving air stream and deflected by the deflector plate until the gasoline and air are properly mixed.

The form of the invention shown in Figure 4 is of the fixed type, the deflector head being placed in a position to operate most efficiently under varying engine speeds. In this case, the means *d* is again utilized.

The invention may be utilized in various combinations and associations and for many purposes other than that specified, as for instance, with compressors, exhausters, and pressure reducing and increasing apparatus. Furthermore, fluids may be combined either in the device or prior to being conducted to the device. The heating arrangement may or may not be utilized.

It is obvious that various changes and modifications and variations may be made in practicing the invention in departure from the particular showing of the drawing and description as given without departing from the true spirit thereof.

I claim:

1. A fuel separator and vaporizer, comprising

an annulus having two portions of different diameter with a shoulder therebetween, a movable deflector plate above the portion of lesser diameter whereby fuel passed through said annulus 5 will impinge against said deflector plate and in part be directed upon said shoulder, resilient means for automatically adjusting said plate axially to compensate for pressure variations in the fuel flow, and means communicating with the atmosphere and cooperating with the resilient means to control the movement of said plate.

2. A fuel separator and vaporizer comprising an annulus having two portions of different diameter with a shoulder therebetween, a tubular member spacedly confined by the lesser diameter of the annulus, a resiliently mounted deflector plate above the portion of lesser diameter and said tubular member, said tubular member being formed with a slot adjacent the lowermost 20 end thereof, and whereby when fuel mixture is passed through said tubular member, the same will impinge against said deflector plate and in part be directed upon said shoulder, any excess of said fuel being received in the space between 25 said tubular member and the annulus of lesser diameter for passage through said slot.

3. In a fuel separator and vaporizer, an annulus having two portions of different diameters with a shoulder therebetween, a deflector plate 30 above the portion of lesser diameter and whereby

fuel passed through said annulus will impinge against said deflector plate and in part be directed upon said shoulder, a sylphon bellows secured to said deflector plate, and atmospheric controlled means in communication with the interior of said sylphon bellows to in turn regulate the movement of the sylphon bellows and said deflector plate.

4. A fuel separator and vaporizer, comprising an annulus having two portions of different diameter with a shoulder therebetween, a resiliently mounted deflector plate above the portion of lesser diameter of said annulus, said deflector plate having an annular concavity, the axis of which is included within the axis of the annulus, a tubular member spacedly confined within the portion of lesser diameter of the said annulus and secured to said annulus at one end thereof, any fuel mixture being adapted to be directly passed through said tubular member for impingement against said deflector plate to in turn be directed upon said shoulder, excess of fuel mixture being received between the tubular member and the annulus, and means formed in the walls of the tubular member whereby fuel mixture so directed as aforesaid is returned to any fuel mixture passed through said tubular member.
